UNITED STATES PATENT OFFICE.

JOHN ROYDEN PEIRCE, OF NEW YORK, N. Y.

MARBLE-POLISHING MACHINE.

No. 843,624.

Specification of Letters Patent.

Patented Feb. 12, 1907.

Application filed June 4, 1906. Serial No. 319,976.

To all whom it may concern:

Be it known that I, JOHN ROYDEN PEIRCE, a citizen of the United States, residing in the borough of Manhattan, city, county, and State of New York, have invented certain new and useful Improvements in Marble-Polishing Machines, of which the following is a specification.

This invention aims to provide an improved polishing head or tool for smoothing and polishing the surface of marble and similar stones. These tools are especially designed to be used in connection with the machine illustrated in my Patent No. 817,798, dated April 17, 1906, though the improved tool is also adapted for use in a variety of other machines. The material may be any of those described in the aforesaid patent or any other of the numerous materials which are used in this art in accordance with the stone to be polished.

The tool is of that class in which the polishing material is a fixed part of the tool in contradistinction to tools which serve only to rub loose sand or other material between the tool and the face of the stone. The material is so arranged in its holder that practically all of it may be used before the "head" (in which term I include the holder and the polishing material together) is discarded. The head is designed to be attached instantaneously to a shaft for rotating it.

Other advantages are referred to in detail hereinafter.

35 The accompanying drawings illustrate an embodiment of the invention.

Figure 1 is a perspective view of a head, showing the working-face of the material. Fig. 2 is a vertical section showing the head connected to a shaft. Fig. 3 is a plan of the head. Fig. 4 is an under side view of the metal plate, and Fig. 5 is a perspective view of one of the sections of polishing material.

Referring to the embodiments of the invention illustrated, the polishing material—as, for example, alundum—is formed in sections A, having a flat bottom face for polishing and preferably also a flat top face for fastening to a metal plate B. The sections A are of such size that a number of them may be arranged on the under face of the plate B in the manner shown in Fig. 1, so as to form a substantially complete ring with a large central hole C and with radial passages D between the several sections and extending throughout the height of the polishing mate-

rial. The under side of the plate B is preferably provided with slight radial ribs E and circumferential ribs F and G, which outline pockets into which the sections A of polishing material are to set. The prime function of the ribs E, F, and G is merely to accurately determine the location of the sections of polishing material, and they are made only deep enough for this purpose. The sections are fastened to the plate B by means of any suitable cementing medium, such as shellac N.

The upper face of the plate B is provided, as shown in Fig. 3, with a number of ribs H, the sockets between which are adapted to receive the teeth J of the base K, which is rotated by the shaft L through a ball-and-socket joint M. The shaft L and base K, as well as the plate B, are centrally apertured corresponding to the central aperture C of the polishing material. This construction provides a number of cutting edges of the polishing material, in front of which are clear spaces D for carrying a supply of water. The central opening C is so large compared with the outer diameter of the wheel as to make the linear velocity of the outer edge not much greater than that of the inner edge, and thus to maintain an approximately uniform rate of wear of the abrading material and a substantially even working face. The water-supply is maintained over substantially the entire face of the tool from the center to the outer edge, and numerous experiments have confirmed the increased efficiency of the tool due to the passages D. These passages are maintained by reason of the peculiar construction adopted until the last bit of polishing material is worn away. Water is introduced in large quantity through the hollow shaft L, as indicated by the arrow.

The ribs H alternate in position with the underneath ribs E, so as to stiffen the plate around its entire length and to permit of casting the plate very thin and light.

While the ribs F and G serve only to locate the sections, the radial ribs E have an additional function in bracing the sections against the tangential strains occurring in use, and thus relieve the shellac from such strains—at least to a great extent. Without these ribs or some equivalent device it is doubtful if the shellac would be sufficient for practical service.

Though I have described with great particularity of detail certain specific embodi-

ments of my invention, yet it is not to be understood therefrom that the invention is restricted to the exact embodiments disclosed.

Various modifications in detail and in the arrangement and combination of the parts may be made by those skilled in the art without departure from the invention.

What I claim is—

1. A tool for polishing marble or the like; including in combination a number of sections A of fixed polishing material, and a common metallic plate B having a central opening, said sections A being cemented to the under face of the plate B in such positions as to leave passages D between them, and a central opening C communicating with said passages and with the central opening in the plate, said plate having ribs E F and G on its under face projecting only sufficiently to determine the location of the sections of polishing material, so that said sections are separated from each other and their vertical faces are exposed throughout substantially their entire depth, whereby the face of the tool is provided with a number of cutting edges in front of which are clear spaces for carrying a supply of water for keeping the marble cool, and which edges are automatically maintained operative throughout the entire usable depth of the tool.
2. A tool for polishing marble or the like,

including in combination a number of sections A of fixed polishing material, and a common metallic plate B having a central opening, said sections A being cemented to the under face of the plate B in such positions as to leave passages D between them, and a central opening C communicating with said passages and with the central opening in the plate, said plate having ribs E F and G on its under face projecting only sufficiently to determine the location of the sections of polishing material, so that said sections are separated from each other and their vertical faces are exposed throughout substantially their entire depth, whereby the face of the tool is provided with a number of cutting edges in front of which are clear spaces for carrying a supply of water for keeping the marble cool, and which edges are automatically maintained operative throughout the entire usable depth of the tool, said plate having also radial ribs H on its upper face forming between them sockets for receiving the teeth of a rotating driving member.

In witness whereof I have hereunto signed my name in the presence of two subscribing witnesses.

JOHN ROYDEN PEIRCE.
